TELEVISION METHOD AND APPARATUS

Application filed November 5, 1929. Serial No. 404,902.

This invention relates to television systems and with particularity to methods and apparatus for scanning and reproducing an image or other visual representation.

be viewed simultaneously by a group of observers.

A further feature relates to the manner of adjustably mounting a television reproducing lamp on the interior of a drum scanner.

A still further feature relates to the details of construction whereby a compact, efficient and economical television receiver can be produced.

Other features and advantages of the invention not specifically enumerated will be apparent after a consideration of the following detailed descriptions in the appended claims. 60

Referring to the drawings,

Figure 1 shows a side view in elevation with part of the cabinet removed to show the interior arrangement and construction of the television set:

Fig. 2 is a front view of the television set 70 with the front wall of the cabinet removed;

Fig. 3 is a detailed view showing the viewing opening and the lens system mounted within the cabinet;

Fig. 4 is a detailed view showing the relation between the drum scanner and the disc shutter according to the invention. 75

Referring more particularly to Figures 1 and 2 there is shown a cabinet of suitable material such as hard wood, or the like, having a base portion 1, a rear wall 2, a front wall

3, and a top 4, the latter being preferably connected by hinges so as to provide ready access to the interior of the cabinet. Secured rigidly to the rear wall 2 is a bracket having the 85

slanting side arms 6 and a table portion 7 formed integrally therewith. The table portion 7 is provided with a central opening 8 through which passes the shaft 9 of a motor 10. Motor 10 is rigidly secured to the table 7 by suitable bolts 11, or in any other convenient manner.

ient manner. Fastened to the upper end of the motor shaft 9 is a spider 12 to which is rigidly attached in any suitable manner a hollow drum 13. Drum 13 is provided with

a series of perforations 14 and so arranged that the line joining the centers of the perforations traces a plural-turn helix around the periphery of the drum. While in the drawing the drum is shown with the perfora-

tions arranged in four complete turns it will be understood that any other number of turns may be employed depending upon the size and detail required in the reproduced image.

5 The upper end of shaft 9 has secured thereto a worm gear 15 which drives a corresponding gear 16 attached to shaft 17. Shaft 17 is provided with suitable bearings in brackets 18, 19 which are rigidly attached to or formed integrally with the table portion 7. Shaft 17 supports at its front end a disc or shutter 20. As shown more in detail in Figs. 2 and 4 member 20 is provided with three curved slots 21, 22 and 23 respectively, the function of each slot being to expose, at any instant, only one perforation in the drum 13. Inasmuch as the disc shaft 17 is eccentric with respect to the axis of rotation of the drum 13 it is necessary that the slots in disc 20 be specially designed for this purpose so as to give, in effect, a substantially uniform "rise" at the point A (Fig. 4) for each equal angular displacement of the disc. Thus in one embodiment of the invention there were 15 forty-eight perforations in drum 13 adapted to cover a picture field approximately $1\frac{1}{2}$ " square and using a three-slot shutter such as shown in Fig. 4. The slots were designed to give a uniform rise of approximately 0.075" 20 for each six degrees of the disc—the gears 15 and 16 being designed to rotate the drum 13 and the disc 20 in the ratio of twelve to one. Thus in order to cover the complete picture field the drum 13 is given four complete turns 25 and during these four turns the disc 20 turns through an angle of 120 degrees whereby the slot 23, for example, successively exposes, one at a time, each of the openings 14.

As shown more clearly in Figure 1 attached to the table 7, preferable integral therewith, is a U-shaped bracket 24 which carries an aperture plate 25 having a central cut-out portion, the width of which is determined by the spacing between successive perforations in drum 14. Attached to the top of bracket 24 is a screw threaded member 26 on which is adjustably mounted by means of thumb nuts 27 a lamp holding bracket 28. Bracket 28 is formed in two sections hinged 40 together as indicated by numeral 29 (Fig. 2). Pivottally attached to one part of member 28 is a screw threaded member 29' which is adapted to register with a pair of ribs 30, on the other half of the lamp support. An 45 adjustable wing nut 31 is provided firmly to grip the base 32 of the lamp 33. Lamp 33 is preferably of the so-called gaseous glow type employing, preferably, a flat plate electrode 34 and a co-operating electrode 35 mounted 50 in very close relation thereto. Electrode 34 is preferably of the same size, or slightly larger in area than the picture field that is scanned by drum 13.

Thus in the example above assumed electrode 34 will be of the order of $1\frac{1}{2}$ " square.

While any convenient gas filling may be employed for lamp 33 it is preferred to employ a filling of neon, or other similar gas. Lamp 33 may be provided with the usual prong terminals 36 adapted to receive a corresponding plug receptacle 37 which is connected by conductors 38 to suitable binding posts 39 mounted on the wall of the cabinet. As shown more clearly in Figure 3 the front wall 3 of the cabinet is provided with a square opening and attached to the edges of said opening by suitable screws 40 is a re-entrant housing having tapered walls 41. Mounted in any convenient manner within the small end of the housing is a large spherical lens 42 which is in optical alignment with the electrode 34 of the lamp 33. Inasmuch as the lamp 33 is closely adjacent to the wall of drum 13 no optical system is required between the lamp and the drum, and the function of lens 42 is simply to magnify the picture field. Furthermore, because of the re-entrant tapered housing the picture field may be viewed simultaneously by a number of observers and the picture field is effectively screened from outside disturbing light sources.

It will be understood that suitable switches may be conveniently mounted on the front of the cabinet for controlling the motor 10 and the lamp 33, as well as for controlling a loud speaker, if such be desired. Inasmuch as any well known switching arrangements may be employed for these purposes it is deemed not necessary to illustrate them in the drawings.

From the foregoing it will be seen that the scanner provides a picture field which is rectangular in shape because of the equal radial distances of the perforations 14 and since the drum 13 is provided with a number of convolutions of perforations the picture field is correspondingly increased in size, and since each slot in the disc 20 covers the complete picture field the disc may be made much smaller than is practical with prior art arrangements. Consequently there is provided a very compact television device which has a large picture field and wherein the light source may be placed in close proximity to the wall of the scanning drum.

While the invention is particularly well suited to use as a television reproducer it will be understood that it can equally well be applied to a television transmitter or analyser in which case the lamp 33 may be replaced by any well known form of photo-electric cell and the image or view to be transmitted would be projected by a suitable optical system represented by lens 42 upon the wall of the drum. Furthermore, while specific dimensions and arrangement of apparatus are disclosed it will be understood that the invention is not limited thereto since the number of perforations in the drum 13 and the number of slots in the disc 20 may be determined in accordance with

the relative speeds at which the respective elements are to be driven and in accordance with the required size and detail of the reproduction. Similarly, while the drum 13 and the disc 20 may be made out of any suitable material it is preferred to employ for this purpose a light metal such as aluminum, or the like, which is capable of accurate machining and provides the required rigidity during operation.

Claims:

1. Television apparatus comprising a hollow cylinder having a series of minute scanning perforations in the wall thereof arranged in the path of a multi-turn helix, a shutter disc having a plurality of separate arcuate slots converging toward the center of the disc for exposing said perforations one at a time, each slot completely exposing all the perforations independently of the remaining slots, means for mounting the disc so that it rotates tangentially to the wall of said drum, and means for rotating said disc and drum in unison. 75
2. In a television device the combination of an enclosing cabinet having a tapered re-entrant image opening, a lens mounted in the small end of said opening, a motor supported on a wall of said cabinet, a scanning drum attached to the motor shaft, a shutter disc for said drum, and a light translating device mounted within said drum, said light translating device being in optical alignment with said lens. 90
3. In a television device the combination of a drum having "x" convolutions in the peripheral wall thereof of perforations, a rotatable disc having "y" arcuate slots each slot exposing all the perforations independently of the remaining slots, and means for rotating said drum angularly "xy" times the angular rotation of said disc. 100
4. In combination an enclosing cabinet having a tapered reentrant observation opening in the front thereof, a lens in the small end of said opening, a scanning device mounted for rotation within said cabinet with its scanning field in fixed alignment with said opening, said scanning device having a plurality of convolutions of minute scanning elements, an image reproducing light beam, means for adjusting the position of said beam with respect to the scanning field of said device and the opening in said cabinet, and a shutter disc having a series of separate arcuate slots each adapted independently to expose all the scanning elements in the scanning device. 110
5. A television scanning device comprising a drum having a plurality of convolutions of scanning elements in the peripheral wall thereof, a shutter disc for exposing one element at a time, said disc having a plurality of slots each in the form of an incomplete spiral each slot exposing all said elements during a partial revolution of said disc. 115
6. In testimony whereof I have hereunto set my hand on this 1st day of November, A. D. 1929. 120
7. SUMNER DUDLEY HABERLE. 125

In testimony whereof I have hereunto set my hand on this 1st day of November, A. D. 1929.

SUMNER DUDLEY HABERLE.
